UNITED STATES PATENT OFFICE.

ALFRED A. GLIDDEN, OF WATERTOWN, MASSACHUSETTS, ASSIGNOR TO HOOD RUBBER COMPANY, OF WATERTOWN, MASSACHUSETTS, A CORPORATION OF MASSACHUSETTS.

DESIGN FOR A CORD TIRE.

Application filed October 25, 1923. Serial No. 7,598. Term of patent 7 years.

To all whom it may concern:

Be it known that I, ALFRED A. GLIDDEN, a citizen of the United States, and resident of Watertown, in the county of Middlesex and State of Massachusetts, have invented a new and original Design for a Cord Tire, of which the following is a specification, reference being had to the accompanying drawing, forming part thereof.

In this drawing:

Figure 1 is a plan view of a portion of a tire.

Fig. 2 is a transverse section on line 2—2 of Fig. 1, and

Fig. 3 is a perspective view of a portion of the tire.

I claim:

The ornamental design for a cord tire as shown.

ALFRED A. GLIDDEN.
